WIRE BINDING-CLIP.

1,317,416.

Specification of Letters Patent. Patented Sept. 30, 1919.

Continuation of application Serial No. 215,697, filed February 6, 1918. This application filed March 15, 1919.
Serial No. 282,774.

To all whom it may concern:

Be it known that I, EDWIN BALTZLEY, a citizen of the United States, and a resident of Glen Ridge, county of Essex, and State 5 of New Jersey, have invented certain new and useful Improvements in Wire Binding-Clips, of which the following is a specification.

This invention relates to wire clips for 10 binding papers together, and has for its object the production of a clip that is clamped on the papers by being reversed in position thereon; one that will not pick up and carry off other papers; a clip that will serve the 15 purpose of all that class of clips that relies upon pressure for binding papers, and also of that other class that binds with a tack or pointed member, which is pressed through the papers to bind them; a wire clip that 20 will take the place of pins for filing purposes; one that is thin, binds flat and tight, does not bulk up the papers except to the minimum degree, and takes up but little filing space in files and filing cabinets; a 25 clip that binds at its jaw end, and so that no other papers can slip under it; one with open jaws for the free admission of papers until reversed on the papers for binding them, and can be used over and over without 30 losing its binding efficiency, and returns to its open jaw position for the free admission of papers when released from binding pressure; a clip that will bind tight and lock the 35 papers together; and finally one that serves the greatest number of binding purposes.

A clip in accordance with my invention is made of an integral piece of wire bent 40 so as to provide a resilient base at one end and side portions extending therefrom, having binding jaws at their other ends which are open initially and may be readily put in place on the papers. These jaws obtain pressure for binding the papers between them by the reversal of the clip on the papers.

45 By "reversal" of the clip on the papers for binding pressure is meant the act, after having slipped the papers between the open jaws of the clip, of twisting or turning it thereon until it is turned completely over 50 (but not the papers), and those faces of the jaws which were directed outward and away from the papers and did not come in contact with the papers before the clip was reversed, now, after reversal, come in contact with the

papers and bind them tightly together by 55 the tension of the spring base.

One of the binding jaws of my improved clip is preferably smaller than the other, and is adapted to pass inside of and through the larger jaw to the normally open jaw position of the clip, for the free admission of 60 papers between the jaws. A tack or point is preferably provided on the end of one of the jaws, to penetrate the papers to be bound, and the tack, combining with the 65 tension of the binding pressure of the clip, locks the papers tight together. The side portions of the clip are so related, that they have an angular position relative to each 70 other, whereby the clip may be readily put in place on the papers. By providing clips with bases of various suitable forms, the capacity of the clip to hold greater number of papers may be increased to any desired 75 degree. The clip may also be provided with hand holes for facilitating the wider expansion of the jaws by finger and thumb pressure to enable papers to be freely inserted.

Figure 1 is a plan view of a preferred form of clip for use with a few sheets or 80 papers. Fig. 2 is a side view of this clip placed over the margin of papers to be held. Fig. 3 is a side view taken midway of the reversal action by which clamping pressure is obtained. Fig. 4 is a side view taken after 85 the reversal has been completed. Fig. 4^a is like Fig. 4, except that the jaws have been pinched together and the tack of the lower jaw forced into the paper. Fig. 5 is an end view of Fig. 2, and Fig. 6 is an end view of 90 Fig. 4. Fig. 7 is a view like Fig. 4, except that the lower jaw has an obliquely directed point or tack. Fig. 8 is an end view of a somewhat modified form of clip for holding an increased quantity or thickness of papers. 95 Fig. 9 is an end view similar to Fig. 6, and showing the quantity clip of Fig. 8 placed upon a comparatively thick bunch of papers, and reversed into clamping position thereon. Fig. 10 is a perspective view of a modified form of clip in position in which it is placed over the edges of a bunch of papers, and Fig. 11 is a perspective view of the clip of Fig. 10 reversed on the papers into 100 clamping position. Figs. 12 and 13 are perspective views similar to Figs. 10 and 11, but showing a still further modified form of 105 clip, and Figs. 14 and 15 are similar views

of a clip embodying all of the various features claimed herein. Figs. 16, 17 and 18 are respectively perspective, side and end views of still another modified form of clip.

5 The clip is preferably made of a single piece of wire, bent to form a spring base 10 at its rear end, two side portions 11, 12 integral with the base portion, and spaced apart, that is, separated from each other the 10 length of the base portion 10. Said side portions terminate in jaws 13 and 14, one of which 13, is the larger and preferably surrounds the other smaller jaw 14 on three sides, and so that the smaller jaw 14 can 15 freely pass from its open position below the larger jaw, through and inside of it, to a position above the larger jaw, and vice versa. I prefer to make the larger jaw 13 substantially semi-circular, and the smaller jaw 20 14, for the smaller sized clip, with a tack 15 bent from its extreme outer end, to stand outward when not binding papers, and inward when binding them. In the larger clips, in which a tack is ordinarily not 25 required, though it may be used if desired, I prefer the smaller jaw to end in substantially circular form, as shown at 16, Figs. 10, and 11, or in substantially part circular form as shown at 17, Figs. 12 and 13. 30 The jaws may have still other forms when desired.

The tack or point of the smaller jaw does not interfere with the free entrance of papers between the jaws, because it initially 35 points outwardly, that is, away from the papers P inserted therein, as shown in Figs. 2 and 5. When papers are inserted, and the clip reversed in position on the papers, as shown in Figs. 3 and 4, for example, the 40 point 15 is turned inwardly, and by pushing the jaws together, the tack is caused to penetrate the papers and locks the clip on them, so that it cannot be moved by ordinary pulling, pushing or the like, without tearing the 45 papers. It can easily be removed however, when desired, and this is accomplished by "unreversing" the clip, that is to say, turning the clip backward through the position shown in Fig. 3 to that shown in Fig. 2. 50 When applied and reversed to binding position, and pushed into the paper as shown in Fig. 4^a, the clip binds the papers securely, will not permit other papers to slip under its jaws and cannot be lost by slipping off 55 the papers, but may, nevertheless, be readily taken off by turning its backwardly to original insertion position. In the drawings, I show the under jaw as having the locking tack or point 15, but I do not confine myself thereto, as the upper or larger jaw may be 60 provided with a locking point or points, or both jaws may have projecting points within the scope of the invention. The tack or tacks may be inclined, if desired, as shown 65 at 18, Fig. 7, for example. The projecting

points may be shorter than as shown, if desired, all that is necessary, being that they shall cling to the paper, so that the clip may not readily come off. A fairly long and moderately sharp projecting tack or point is 70 preferred however, which will penetrate the papers, and be capable of being pressed farther into the papers, or through the papers as by thumb or finger pressure. And when the tack is made with an oblique angle, 75 as shown at 18, in Fig. 7, the clip may be pushed farther on the papers after it is reversed, and engaged with the papers as by pulling toward the edge thereof, when the tack will penetrate without the clip being 80 necessarily subjected to compression. The oblique angle of the tack or point also facilitates the process of reversing the clip by riding up on the incline so provided.

In practice, I have found it desirable to 85 make the clip of the best spring wire, not only to give adequate gripping tension, but to make the clip permanently useful by returning to proper gripping form after each 90 use, even though stretched beyond its normal capacity. This is notoriously not the case in most commercial wire clips. I also preferably make use of wire of the smallest gage possible, for the service to be performed, for thick wire is not only a danger 95 and a nuisance in letters in the mails, but unnecessarily consumes valuable space in filing cabinets. The thin wire is preferably of the best tempered quality for spring and tension. The thin wire serves a further purpose. For cheapness of construction and adaption to the larger range of service, a clip 100 with a right angular point and made of wire of very small gage, has been found most satisfactory, and the thin wire obviates the 105 necessity of sharpening the point. For some purposes it is an advantage not to sharpen the point beyond the sharpness the thin wire gives it, because while such a point may be readily pressed through the papers, by 110 thumb and finger pressure when desired, without such pressure it may ride on the paper, without penetrating, which is desirable when the papers are very few or thin.

The sides of the clip shown in Figs. 1 and 2 115 are normally or initially at an angle to one another, thus providing normally open jaws for the entrance of papers between them. The reliance for gripping tension is on the force produced by reversal of the clip on the 120 paper, the smaller jaw having a tendency to pass back through the larger jaw to initial position, which movement however, is prevented from taking place by the papers between them and from this the clamping pressure results.

The form of clip shown in Figs. 8 and 9 is adapted for binding a somewhat thicker bundle of papers. Here the back 10^a is not so flat as in Fig. 5, for example, but extends 130

at an angle between the two sides 11^a and 12^a, and in this way serves to accommodate a bunch of papers P' of increased thickness, as will be seen from the end view, Fig. 9.

5 In the forms shown in Figs. 10 and 12, the two sides 11' and 12' (Fig. 10) and 11'' and 12'' (Fig. 12), cross each other so that the planes defined by said sides together with their jaws intersect between the ends 10 of the sides, and the jaws, as 13' and 16 (Fig. 10), are wide apart, while the spring base 10' is extended laterally between its ends into substantially a U-form or V-form, providing for a wide range of expansion or contraction to accommodate its use on bunches 15 of papers of widely ranging thickness. In this form, the plane of the spring base 10' is substantially at right angles to the sides 11' and 12' when in place in a bunch of 20 papers as shown in Fig. 11, and to the planes defined by the sides taken together with their jaws.

In the larger sizes of my clip, I may provide hand holds as 19 and 20 (Figs. 12 and 25 13), in the sides between the spring base and the jaws, and because the sides of the clip cross each other, pressure on the hand holds 19 and 20 spread the jaws 13'' and 17 wider apart, so that papers can the more 30 readily be entered between them. When the papers are thus entered, the clip is reversed on the papers to the position shown on Fig. 13. The clip of Figs. 10 and 11 may be manipulated in a similar manner, the ends 35 of the base 10' and the adjacent parts of the sides 11' and 12' serving as handholds for spreading the jaw apart. Various forms of handholds may be used.

The clips of Figs. 14 and 15 embody a 40 large number of desirable features. The base 100 is of U-form or V-form, and is adaptable for expansion or contraction to be used on bunches of paper of a wide variation in thickness. The sides 101 and 102 have handholds 103 and 104 between the region 45 where they normally cross when not applied to papers, as shown in Fig. 14, and their junction with the base portion. The larger jaw 105 is of substantially semi-circular 50 form, having the open side toward the base, as indicated at 106, and the smaller jaw 107 is provided with an obliquely extending point or tack 108, adapted to penetrate the 55 papers when the clip is put in place, reversed to clamping position (Fig. 15) and then pulled toward the edge of the papers P^a, or 60 compressed thereon, as by pressure applied to the handholds 103 and 104, which handholds are, of course, adapted to be seized and 65 compressed to open the jaws 105, 107 in putting the clip on the paper.

The clip shown in Figs. 16, 17 and 18, is 65 a quantity clip which serves well for binding a comparatively thick bunch of papers. The base 200 extends practically at right angles

to the edge of the papers P^a held therein, as appears from Fig. 18, and the sides 201, 202 may be compressed by thumb and finger pressure applied thereto to widen the initial opening 203 between the jaws 204, 205 in 70 applying the clip to a bunch of papers.

The degree of gripping tension of all the clips illustrated herein, is determined by the width of the normal opening of the jaws, the tension being obtained by reversing the 75 clip on the papers, whereby the pressure is transferred from one side of each of the clip jaws to the other side thereof, and the grip is therefore at the extreme outer or jaw ends of the binding sides, so that other papers 80 cannot slip under them to be picked up and carried off.

Ninety per cent of all the clips used are for binding from two to four or six papers. This use is served by the form of the clip shown 85 in Fig. 1. The other forms of the improved clip shown are adapted for binding larger quantities of papers, the form shown in Figs. 10 and 11 for example, being capable by expansion or contraction for use with a 90 wide range of thickness of papers. It will thus be seen that a clip in accordance with my invention, covers a wide range of applications, and serves the greatest number of 95 clip uses, ranging all the way from binding a few papers to a very thick bunch of papers, which is the highest function of a clip.

This application is a continuation of my application No. 215,697, filed Feb. 6, 1918.

I claim:

1. A paper binding clip for binding papers by being reversed in position thereon, comprising a resilient base portion, two side portions, spaced apart, extending therefrom and ending in jaws, one of said jaws being 105 provided with a substantially pointed end which extends outwardly away from the papers before the clip is reversed, and inwardly toward the papers after it is reversed.

2. A paper binding clip for binding papers by being reversed in position thereon, comprising a resilient base portion, two side portions, spaced apart, extending therefrom and ending in jaws, one of said jaws having 115 a pointed end which extends outwardly away from the papers on an oblique angle before the clip is reversed in position, and inwardly toward the papers on an oblique angle after it is reversed.

3. A binding clip for binding papers by being reversed in position thereon comprising a pair of connected spring clamping arms, one of said clamping arms being provided with an open jaw and the outer end 125 of the other clamping arm passing freely through said jaw from face to face thereof.

4. A binding clip for binding papers by being reversed in position thereon comprising a pair of connected spring clamping 130

arms, the outer end of one of said arms being provided with portions disposed laterally on both sides of the end of the other arm, whereby the latter may pass directly 5 from one face thereof to the other face thereof.

5. A paper binding clip, for binding papers by being reversed in position thereon, comprising a resilient base portion, and two 10 side portions, spaced apart, extending therefrom and ending in jaws, the plane of said base portion being at an angle to the plane of one of said jaws.

6. A paper binding clip having a resilient 15 base portion, and two side portions, spaced apart, extending therefrom and ending in jaws, one of which surrounds the other on three sides, and are arranged to bind papers by being reversed in position thereon, 20 the plane of said base portion being at a right angle to the plane of one of said jaws.

7. A paper binding clip having a resilient base portion, two side portions extending therefrom in crossing planes, ending in 25 jaws, the planes of which are at right angles to the plane of said resilient base portion, and open by compression of said side portions between the point of crossing of said planes and said base portion, one of said 30 jaws being formed to surround an open area on three sides, and the other to coöperate therewith to bind the papers by being reversed in position thereon.

8. A paper binding clip having a resilient base portion, two side portions, spaced 35 apart, extending a distance therefrom, and then deflected at an angle from the plane of said base portion, to form a hand hold thereby, and then in converging and intersecting planes ending in jaws to be opened 40 by compression of said hand holds, said jaws being conformed and arranged to bind papers by being reversed in position thereon.

9. A paper binding clip having a resilient base portion, two side portions spaced apart, 45 extending therefrom, ending in jaws for the entrance of papers between them, one of said jaws being formed to surround an open area on three sides and the other to coöperate therewith to bind papers by being 50 reversed in position thereon.

10. A paper binding clip, for binding papers by being inserted and reversed in position thereon, comprising a resilient base portion, two side portions, spaced apart, extending therefrom and ending in jaws of unequal size adapted for the entrance of papers between them, the larger of said jaws being open at the end thereof toward the base position, and the smaller of said jaws 60 being adapted to pass through the open part of the opposing jaw.

In testimony that I claim the foregoing I have hereto set my hand this 11th day of March, 1919.

EDWIN BALTZLEY.
